UNITED STATES PATENT OFFICE.

J. LEE HADLEY AND HERMAN G. REIBEL, OF WARREN, OHIO, ASSIGNEES TO THE PEER-LESS ELECTRIC COMPANY, OF WARREN, OHIO, A CORPORATION OF OHIO.

SHORT-CIRCUITING DEVICE FOR ALTERNATING-CURRENT MOTORS.

Application filed March 28, 1921. Serial No. 456,412.

To all whom it may concern:

Be it known that we, J. LEE HADLEY and HERMAN G. REIBEL, of Warren, in the county of Trumbull and State of Ohio, have invented certain new and useful Improvements in Short-Circuiting Devices for Alternating-Current Motors; and we do hereby declare the following to be a full, clear, and exact description of the invention, such as

10 will enable others skilled in the art to which it appertains to make and use the same.

Our invention relates to short-circuiting devices for alternating current motors, and the object of the invention is to provide a 15 simple and improved mechanism of this character which will efficiently function to change the circuit connections of the motor after it has reached a desired speed.

In the drawings, Figure 1 is a vertical 20 longitudinal sectional view of a motor equipped with our improvement. Figure 2 is a vertical sectional view on line 2—2, Figure 1, with end plate removed to clearly show the short-circuiting means. Figure 3 shows the governor weights in short-circuiting position. Figure 4 shows a commutator in vertical sectional view of a modified form with governor weights. Figure 5 is a detail of one of the weights.

30 We have shown the motor casing at 1, with bearings 2, 3, for the shaft 4 of the armature 5, and the commutator is indicated at 6.

Our improved short-circuiting device is fitted on the shaft 4 and includes a cage-like 35 member having a hub 10 through which the shaft extends and on which shaft it is removably secured, and plates 12 and 13 which are held in spaced relation to each other by pins 14. Fitted for radial sliding movement 40 between the plates 12 and 13 are weights 15, each of which is of segmental form and has a tongue 16 which lies between pairs of the pins 14 which thus form a guideway for the weights. Each of these segmental weights 45 has a longitudinal groove 17 in its periphery into which an endless coiled spring 18 encircles the series of weights is designed to fit. The tension of the spring is such as to normally retain the segments in a position

50 where the ends of the tongue 16 will be in engagement with the shaft 4, but this tension is not great enough to retain the weights in this position under centrifugal influence. The weights with the encircling spring have 55 an inside position relative to the commutator

bars and under centrifugal action the weights are effective to cause the spring to engage these bars, thus short-circuiting the commutator. In Figures 4 and 5 we have shown a modified form, the weights therein 60 illustrated being of slightly greater width than those previously referred to, and groove 27 extending the length of the periphery to one side of the longitudinal center line, this groove being adapted to receive spring 28 65 which encircles the series of segments. A second groove 29 extending in parallelism with the groove 27 receives small plates 30 transversely fitted in the groove, the plates being compactly arranged, and forming 70 short-circuiting bars which under the force of centrifugal action overcoming the counteraction of the spring 28 will contact with the commutator bars for short-circuiting the commutator and transforming the motor 75 from one operating on the repulsion principle to a motor of the induction type.

We claim as our invention:

1. In a motor, the combination with the commutator, and a rotatable shaft, of a cage 80 secured to said shaft and including a pair of spaced apart plates, radially movable segmental weights fitting between said plates, a short-circuiting means supported by said weights and adapted to engage said commutator under the centrifugal influence of said weights, and a positive guiding means for each of said weights interposed between said plates.

2. In a motor, the combination with the 90 commutator, and a rotatable shaft, of a cage secured to said shaft and including a pair of spaced apart plates, spacing pins between said plates, radially and independently movable weights fitting between said 95 plates, each of said weights having a portion guided by pairs of said pins, and a short-circuiting means supported by said weights and adapted to engage said commutator under the centrifugal influence of said 100 weights.

3. A short-circuiting device for electric motors including, in combination with a commutator, radially movable segmental weights, each of said weights having its 105 arcual periphery grooved, a tension member encircling said weights and fitting within said grooves, such member tending to restrain centrifugal movement of said weights, and adapted to engage said commutator 110

when said weights are moved under centrifugal influence.

4. A short circuiting device for electric motors including, in combination with a 5 commutator, radially movable segmental weights, each of said weights having its arcual periphery grooved, an endless coiled spring encircling said weights and fitting within said grooves, such coil spring tend- 10 ing to restrain centrifugal movement of said weights and adapted to engage said commutator when said weights are moved under centrifugal action.

5. In a motor, the combination with the 15 commutator, and a rotatable shaft, of a cage secured to said shaft and including a pair of spaced apart plates, radially mov- 20 able segmental weights fitting between said plates, each of said weights having its 25 arcual periphery grooved, a tension member encircling said weights and fitting within said groove, said member tending to restrain centrifugal movement of said weights and adapted to engage said commutator when said weights are moved under centrifugal action.

6. In a motor, the combination with the commutator, and a rotatable shaft, of a

cage secured to said shaft and including a pair of spaced apart plates, spacing pins 30 between said plates, radially movable seg- 35 mental weights fitting between said plates, each of said plates having a portion guided by pairs of said pins and its arcual periph- 40 ery grooved, a tension member encircling said weights and fitting within said groove, such member tending to restrain centrifugal movement of said weights and adapted to engage said commutator when said weights are moved under centrifugal action 40

7. A short circuiting device for electric motors including, in combination with the commutator, radially movable segmental weights, a circumferentially arranged ten- 45 sion member in engagement with all of said segmental weights, such member tending to restrain centrifugal movement of said weights and adapted to engage said commutator when said weights are moved under centrifugal action, and an independent 50 guiding means for each of said weights.

In testimony whereof we have signed this specification.

J. LEE HADLEY.
HERMAN G. REIBEL.
